J. HOWELL

PACKING AND STORING CHEST

Filed Jan. 27, 1923

UNITED STATES PATENT OFFICE.

JULIUS HOWELL, OF ST. LOUIS, MISSOURI.

PACKING AND STORING CHEST.

Application filed January 27, 1923. Serial No. 615,260.

To all whom it may concern:

Be it known that I, JULIUS HOWELL, a citizen of the United States, residing at St. Louis, in the county of St. Louis and State 5 of Missouri, have invented certain new and useful Improvements in a Packing and Storing Chest; and I do hereby declare the following to be full, clear, and exact description of the invention, such as will enable others skilled in the art to which it 10 appertains to make and use the same.

The invention has for its object the provision of a chest for packing and storing purposes which is vermin and moisture 15 proof, comparatively cheap and ornamental and attractive in appearance, to constitute an article of furniture.

The chest forming the subject matter of the present invention is designed to receive 20 clothing, and articles of wearing apparel, such as furs and woolen goods which are required to be protected from the ravages of the moth.

Other objects and advantages will be apparent and suggest themselves as the nature 25 of the invention is understood.

While the drawings illustrate an embodiment of the invention it is to be understood that in adapting the same to meet different 30 conditions and requirements, various changes in the form, proportion and minor details of construction may be resorted to without departing from the nature of the invention.

Referring to the accompanying drawings 35 forming a part of the application,

Figure 1 is a perspective view of a chest embodying the invention, the lid being shown in open position,

Figure 2 is a transverse sectional view of 40 the same, the lid being closed, and

Figure 3 is a sectional detail.

Corresponding and like parts are referred to in the following description and designated in the several views of the drawings 45 by like reference characters.

The chest illustrated in the drawing is of rectangular form and comprises the front and rear walls 10 and 11, the end walls 12, the bottom 13 and the top or cover 14 which 50 is hinged at 15 and may be provided with

the conventional retaining or limiting connection 16.

The several walls of the receptacle are provided with marginal frames which, when those of the side and end walls are joined to 55 the standards or legs 17, constitute a skeleton frame. The bottom may be of uniform thickness or paneled as preferred.

The side walls, and more particularly the front and end walls, are provided with 60 panels 19 which preferably consist of cement or analogous plastic material, preferably molded in the marginal frames and having facial inserts of glass, as shown at 20, or like material. These inserts are irregular 65 in outline and consist of small pieces of broken glass of various colors which produce an ornamental and pleasing effect, both by reason of the contrasting colors and the variety of outline of the inserts. These inserts 20 reinforce the panels or slabs and guard against fracture by reason of an arrangement to break joint. The panels or slabs are further reinforced by rods or stays 21 molded therein. A lining 22 covers the 70 inner side of each slab or panel 19 and is held in place by strips or molding 23 overlapping the joints and secured to the marginal framing. A molding 24 attached to the inner edge of the skeleton frame prevents 75 outward displacement of the panels 19 and the lining 22.

It will be obvious that as the chest consists essentially of a skeleton frame and the fillers are of a comparatively cheap material, 80 the container having the characteristics above indicated may be made in comparatively large sizes and at a relatively small cost and yet afford a sufficient protection and be sufficiently durable to answer all of 85 the purposes of the conventional forms of packing and storing chests. The lining 22 preferably consists of thin wood, such as mahogany, and serves to cover the panel and protect the same besides giving a finished 90 appearance to the interior of the chest.

Having thus described the invention, what I claim as new is:

1. A chest of the character specified comprising a skeleton frame, a panel therein of 100

plastic material having facial inserts of glass of irregular shape and vari-colored, a molding preventing outward displacement of the molded frame, a lining covering the rear side of the panel, and strips retaining the lining in place.

2. A packing and storing chest having its walls provided with marginal frames, reinforced panels of molded cementitious

material fitted into said frame, and the front ¹⁰ of said panels having inserts of irregular shape and contrasting color.

In testimony whereof I affix my signature in presence of two witnesses.

JULIUS HOWELL.

Witnesses:

JOHN W. YUNG,

WILLIAM SKIDMORE.
